CLAIM

The ornamental design for a brush attachment for skate board or similar article, as shown and described.

DESCRIPTION

FIG. 1 is a front perspective view of a brush attachment for skate board or similar article showing my new design;

FIG. 2 is a top plan view thereof on an enlarged scale;

FIG. 3 is a rear elevational view thereof;

FIG. 4 is a side elevational view thereof;

FIG. 5 is a front elevational view thereof;

FIG. 6 is a front elevational view of a modified form of

the design shown in FIGS. 1 through 5; and

FIG. 7 is a side elevational view thereof.
